UNITED STATES PATENT OFFICE.

FRANK E. RUPE, OF HARTFORD, CONNECTICUT, ASSIGNEE TO ROYAL TYPEWRITER COMPANY, INC., OF NEW YORK, N. Y., A CORPORATION OF NEW YORK.

MACHINE FOR TESTING THE ADJUSTMENT OF TYPE OF TYPE-WRITING MACHINES.

1,216,611.

Specification of Letters Patent. Patented Feb. 20. 1917.

Application filed November 27, 1915. Serial No. 63,706.

To all whom it may concern:

Be it known that I, FRANK E. RUPE, a citizen of the United States of America, residing in Hartford, in the county of Hartford and State of Connecticut, have invented a certain new and useful Machine for Testing the Adjustment of Type of Type-Writing Machines, of which the following is a specification.

10 In securing the type to the type bars of typewriting machines, which is generally done by a soldering process, it is practically impossible to preliminarily set all of the type in proper working positions. Type-writing machines duly assembled have to be tested to determine whether the type are properly set on the type bars. To correct defective settings of the type, the type bars have to be removed from the machine after 20 the type bars are disconnected from their actuating means and the defects corrected by resoldering. This, of course, necessitates considerable handling of the mechanism by the testing operator and to avoid this and otherwise facilitate such testing and adjusting is the object of this invention. With this object in view a special testing machine is provided which in all essential respects is similar to the regular working machines. 25 It is however provided with an auxiliary set of bars or fingers carried by a segment located in the machine just below the regular type bar segment, said fingers being connected to the key levers in substantially the same manner as are the type bars in the working machine. This auxiliary segment is secured to the side frames of the machine, and the regular working segment, with the type bars connected thereto, is secured in operative position by readily controlled means and held in the testing machine in the same position relative to the platen, etc., that it will occupy in a working machine. There is of course an auxiliary finger for each type bar, located immediately below or behind the same but not normally connected thereto, the arrangement being such that the ends of the fingers engage the type bars and raise them into 50 printing positions as the key levers are manipulated.

As illustrated in the accompanying drawings, the invention is shown applied to a machine of the Royal Standard type.

Figure 1 is a central sectional view of the machine:

Fig. 2, a view of detached parts showing a type thrown into printing position by an operating finger:

Fig. 3, a plan view of the auxiliary segment and a working segment showing their relative positions: and

Fig. 4, a front elevation of the same.

The testing machine of this invention is similar in general construction to the regular Royal Standard machine, comprising key levers 5 pivoted at their rear ends to a bar 6 which is secured to the sides 7 of the main frame, front levers 8 having their pivotal connections to a bar 9 also secured to the sides 7, vertical links 10 connecting the front levers 8 to the key levers 5, horizontal links 11 extending rearwardly from the front levers, links or rods 12 connecting the links 11 to the universal bar 13, springs 14 on these rods 12 attached to an adjustable spring frame 15, a type head rest 16, carriage support and shift frame 17, carriage 18, platen 19 and platen feed mechanism 20.

The new added devices adapting the machine for the purposes of this invention consist of a series of bars or fingers 21 pivoted at 22 to a segment 23 and connected at 21* to the links 11. The segment 23 has side wings or extensions 24 and is securely held between the sides 7 of the main frame by screws 25, as shown at Fig. 4. It is also provided with slots for the auxiliary bars or fingers 21 and with a bearing rod for the fingers similar in construction to the slots and bearing rods of the regular type bar segments. The radius of the pivotal connections of this segment 23 with the fingers 21 is sufficiently greater than the radius of the pivotal connections 26 of the regular type bar segment 27, with its type bars 28, to permit segment 23 to surround segment 27, as clearly shown at Fig. 4.

Type bar segments are made interchangeable, each one being provided with a type guide 29, which is secured to the segment plate by screws 30, and are also made up with a complete set of type bars. These segments, so equipped, are adapted to be set and held in proper working position in the testing machine by dowel pins 31 and screws 32, there being suitable provisions on

the machine for such attachment of a segment thereto. When so located, the type bars 28 and the actuating bars or fingers 21 are arranged in parallel circles, or segments 5 of circles, the arrangement being such that each of the fingers 21 is behind or beneath the type bar whose type corresponds to the character of the key levers connected to its actuating finger. The type bars 28 are not 10 directly actuated by the key levers and are in no way connected to any working member of the testing machine, thus greatly simplifying the work of applying them to said machine. The fingers 21 are plain bars,— 15 that is they are without type,—and are adapted, by their free ends striking the under side of the type bars, to throw the type bars 28 into printing position toward the platen 19 as the key levers are manipulated, as shown at Fig. 2.

The type 33 are secured to the ends of the bars 28, preferably by a soldering process, as closely as possible to correct impression position; and, with the bars duly assembled 25 in a segment 27 and with the segment secured in the testing machine, the adjustment of the type is determined by operating said machine. The type that are found out of alinement, or otherwise disarranged, are 30 marked or suitably indicated as a guide for the type attaching operator to reset such imperfectly disposed type, the segment with the type bars attached being detached from the testing machine for this purpose. With 35 the type closely approximating correct printing positions on their respective type bars, the segment is placed in the working machine in which it will be permanently used and the final close adjustment of the 40 type is made in the usual manner.

I claim:

1. A machine for testing the adjustment 45 of type of typewriting machines comprising key levers and a platen and adapted to hold a set of unconnected type bars and provided with a series of devices connected to the key levers for individually actuating the type bars.

2. A machine for testing the adjustment 50 of typewriting machines, comprising key levers, a platen, a fixed type bar segment, type bars carried by the segment, and a

series of devices connected and operated by the key levers and each of which is adapted to engage and operate a type bar. 55

3. A machine for testing the adjustment of type of typewriting machines comprising key levers and a platen and adapted to hold a type bar segment to which is attached a set of unconnected type bars and provided 60 with pivoted fingers connected to the key levers and arranged to throw the type bars into printing position when the key levers are manipulated.

4. A machine for testing the adjustment 65 of type of typewriting machines comprising key levers, a segment, fingers pivoted at one end to the segment, connection between the key levers and fingers, and a platen, in combination with a detachable type bar segment and type bars pivoted thereto, said 70 type bars being in the range of movement of the fingers so as to be actuated thereby as the key levers are depressed.

5. A machine for testing the adjustment 75 of type of typewriting machines comprising key levers, a segment, fingers pivoted at one end to the segment, connection between the key levers and fingers, and a platen, in combination with a detachable type bar segment 80 having its axis common with the finger segment and type bars pivoted thereto, said type bars being in radial lines with the fingers, substantially as described.

6. A machine for testing the adjustment 85 of typewriting machines comprising key levers, a segment, fingers pivoted at one end to the segment, connections between the key levers and fingers, and a platen, in combination with a detachable type bar segment 90 and type bars pivoted thereto, the pivotal connection of the fingers with their segment being in front of the pivotal connections of the type bars with their segment, said type bars being in the range of movement of the 95 fingers so as to be actuated thereby as the key levers are depressed.

In testimony whereof, I have hereunto subscribed my name.

FRANK E. RUPF.
